UNITED STATES PATENT OFFICE.

HERBERT W. DAY, OF WOLLASTON, MASSACHUSETTS, ASSIGNOR TO SPRAY ENGINEERING COMPANY, OF BOSTON, MASSACHUSETTS, A CORPORATION OF MASSACHUSETTS.

MECHANISM FOR APPLYING COATING TO SHELLS AND OTHER ARTICLES.

1,347,994.

Specification of Letters Patent. Patented July 27, 1920.

Application filed June 22, 1917. Serial No. 176,317.

To all whom it may concern:

Be it known that I, HERBERT W. DAY, a citizen of the United States, and a resident of Wollaston, in the county of Norfolk and 5 State of Massachusetts, have invented an Improvement in Mechanism for Applying Coating to Shells and other Articles, of which the following description, in connection with the accompanying drawings, is a 10 specification, like characters on the drawings representing like parts.

This invention relates to mechanism for applying paint or other coating material to ammunition shells and other articles and 15 more particularly to means for applying coating material to the exterior and to the interior of large and heavy shells.

In order that the principle of my invention may be readily understood, I have 20 disclosed certain embodiments of my invention in the accompanying drawings, wherein—

Figure 1 is a view partially in front elevation and partially in vertical section of one 25 form of mechanism embodying my invention;

Fig. 2 is a view mainly in horizontal section of a portion of the mechanism shown in Fig. 1.

While I have herein represented my 30 invention as applied to the coating of ammunition shells with paint, it is evident that my invention may be employed in other relations and in the application of a coating to other articles whether hollow or solid.

Referring to those specific applications or 35 embodiments of my invention herein shown, an important object thereof is to provide means whereby hollow articles, such for example as an ammunition shell, may be 40 readily coated, in certain cases exteriorly and in other cases interiorly, or both exteriorly and interiorly, so that a large number of such articles may be treated in a minimum length of time.

Referring more particularly to the drawings 45 and first to that form of my invention shown in Figs. 1 and 2, wherein I have provided means for coating the shell or other article exteriorly, I have therein represented a table 50 or support at 1, it being provided with suit-

able uprights 2 connected if desired by cross pieces not herein illustrated. The said table or support 1 is provided with a suitable opening 3 extending vertically therethrough and having therein a suitable sleeve-like bearing 4 formed with or extending from a yoke like member 5 or frame secured to said table 1 and adapted for the reception of a shaft 6, the lower end 7 whereof is stepped in the lower portion of said yoke-like member 5. Above said opening 3 is provided a member 8 pinned to said shaft, and between the bearing 4 and member 8 is interposed a suitable anti-friction device such as a ball bearing 9. Upon the upper 60 end of said shaft 6 is adapted to be securely supported the shell or other article 10 that is to be coated and which in this case is an ammunition shell. The said shell is positioned within a casing 11, which may be 65 of any suitable form. Entering said casing 11 is the coating or spray means preferably composed of one or more spray nozzles. In this form of my invention, I have represented three spray nozzles 12, 13, 14, which 70 are of any suitable character, but preferably are of the general type shown in the patent to Aubrey G. Eneas, No. 1,101,264, dated June 23, 1914. Preferably the said nozzles 75 are so relatively positioned that the material discharged therefrom coats the entire lateral surface and the upper end of the shell when the latter is rotated, as indicated in Fig. 1.

The nozzle 12 is mounted upon the end of a pipe 15 and the nozzles 13 and 14 are 80 mounted upon a pipe 16, both of which pipes are in communication with a pipe 17 through which the material is received from any suitable source of supply and preferably, though not necessarily, through instrumentalities like those shown in my Patent No. 1,201,219, dated October 10, 1916.

Referring to that specific means herein shown for supplying coating material to the one or more spray nozzles, the paint or other 95 liquid that is to be applied to the shell is contained within a suitable tank 18, preferably having a loose fitting cover and supported by the discharge pipe 19 above the level of the top of the shell 10. The said 100

discharge pipe 19 is suitably supported at 20 upon or by the table or support 1 and if desired may have a suitable outlet through which the contents of the tank 18 may be drawn off. The said pipe 19 is herein represented as provided with a suitable valve 21, and is also represented as provided with a fitting 22 having tapped thereinto a discharge pipe 23 provided with a valve 24.

10 Secured to the discharge pipe 23 is a fitting or valve casing 25 containing a valve 26 which while it may be of any suitable type is preferably a charge or measuring valve similar to the valve 56 shown in my said Patent No. 1,201,219, and which therefore need not be more fully described. Operatively connected with and extending from said valve 26 is an arm 27 to which is pivotally connected a link 28 reaching downward to a treadle, not shown, and by means of which the valve may be periodically opened. Any other suitable means to operate the said valve may be employed. Also operatively connected to the said valve 26

15 is an arm 29 to which is pivotally connected a link 30 itself pivotally connected to an arm 31 rigid with a compressed air control valve 32, whereby when the valve 26 is open, air may be admitted through the valve 32 to

20 discharge the air through the valve to the several nozzles 12, 13, 14. Said valve 32 is preferably similar to the corresponding valve shown in my co-pending application Serial No. 137,945, filed December 20, 1916.

25 Air under pressure is admitted to the valve 32 from any suitable source, herein indicated at 33, into a coupling 34, to which is connected an exhaust pipe 35 and a pipe 36 leading to a pump-like or bellows member 37 preferably similar to that shown in my said co-pending application Serial No. 137,945. The said pump-like member 37 is preferably provided with ball check valves and leading from one of said valves is a pipe

30 38 extending to and in communication with the pipe 39 in communication with the coupling or fitting 34 and leading back through a pipe 40 to the source 18 of coating supply. The pipe 36 is in communication with the

35 valve 26 and hence a circulation may be and is effected through the said valve as set forth in my said co-pending application. In order to operate the pump member 37 I provide a rod 41 that is preferably connected

40 to the treadle as set forth in my said co-pending application.

The shell 10 may be supported upon the upper end of the shaft 6 in any suitable manner. Herein for the purpose and as

45 shown most clearly in Fig. 2, I have provided a bracket 42 supported upon a suitable standard 43 and having two spaced rolls 44 to engage the rotating surface of the shell. Preferably substantially opposite said roll

50 44 I provide a bar 45 having a roll 46 to

engage the shell and adjustably secured by bolts 47 entering elongated slots, to the door or other closure 48 of the casing, whereby when the door is closed the roll 46 engages the shell, thus providing a three-point support for the upright shell. 70

I provide any suitable means to rotate the upright shaft 6 whereon the shell 10 or other article is supported. Herein for the purpose I have provided the said shaft 6 with 75 a disk 49 fast thereon and below the table or support 1, and with which frictionally engages a driving pinion 50 fast upon a horizontal shaft 51 that is mounted in a suitable bearing 52 in said yoke-like member 5 and in 80 a bearing 53 upon the upper end of a post or rod 54 that is mounted for vertical movement in the member 5. The shaft 51 is driven in any suitable manner and preferably by a pulley 55 fast thereon. Also 85 mounted upon said shaft 51 is a pulley 56 about which passes a belt or driving band 57 that also passes about a pulley 58 fast on a short shaft 59 mounted in a suitable bearing 60 in a bracket 61, said bracket being 90 supported at the upper end of a standard 62 rising from and secured to the table or support. Upon the shaft 59 is a fan 63 that is mounted in an outlet 64 of the casting 11, the purpose of said fan being to exhaust 95 from the casing surplus coating material and fumes or vapors incident to the coating operations.

Preferably I provide means whereby the closing of the casing 11 initiates the relative 100 movement of the shell or other article and the coating means, and herein and preferably the rotation of the shell or other article to be coated, and conversely the opening of the casing stops such rotation. For this 105 purpose I have herein represented the door or closure 48 as mounted for rocking movement upon an upright rod 65 suitably supported in the casing and passing downwardly through an opening in the table or 110 support 1, and to the lower end of which is suitably connected a rock arm 66 that is pivotally and preferably adjustably connected to a link 67 which in turn is pivotally connected to an arm 68, itself pivotally connected to the lower end of and serving to support the rod 54. Preferably also mounted upon the rod 65 in proximity to the disk 49 is a brake 69. The construction and relation of parts are such that when the door 48 115 is closed the roll 46 is brought into guiding or supporting engagement with the shell 10 and the pinion 50 is lifted into engagement with the disk 49, it being understood that the bearing 52 for the shaft 51 is such as to 120 permit a rocking movement of said shaft 51. Conversely upon the opening of the door the shaft 51 is rocked downward withdrawing the pinion 50 from the disk 49 and the brake 69 is brought into engagement with the pe- 125

riphery or edge portion of the disk 49, thereby quickly stopping the same.

Instead of friction drive means for the shell or other article 10 any other suitable 5 drive means may be provided, as for example toothed gearing.

Having thus described several illustrative embodiments of my invention, I desire it to be understood that although specific terms are 10 employed, they are used in a generic and descriptive sense and not for purposes of limitation, the scope of the invention being set forth in the following claims:

1. Mechanism for applying coating comprising an article support, coating means, an inclosing casing for said article support and having a closure, driving means for the article support, and means operatively connected to said closure to impart relative movement to said coating means and the article support.

2. Mechanism for applying coating comprising an article support, coating means, an inclosing casing for said article support and 25 having a closure, means to impart relative movement to the article support and coating means, and means operatively connected to said closure to move said means for imparting said relative movement.

3. Mechanism for applying coating comprising an article support, coating means, an inclosing casing for said article support and having a closure, driving means for said coating means, and means operatively connecting said closure and driving means to rotate the article support.

4. Mechanism for applying coating comprising an article support, coating means, an inclosing casing for said article support and 40 having a closure, driving means for the article support, a brake, and means operatively connected with said closure to control said brake.

5. Mechanism for applying coating comprising an article support, coating means, an inclosing casing for said article support and having a closure, driving means for the article support, a brake, and means connected to said closure whereby closing movement of 50 said closure moves said article support, and opening movement thereof stops said driving means and applies said brake.

6. Mechanism for applying coating comprising an article support, an inclosing casing therefor having a door, means for containing a predetermined quantity of coating material, means forcibly to discharge said material upon said article, driving mechanism for the article support, and means operatively connecting said door and said driving means.

7. Mechanism for applying coating comprising an article support, an inclosing casing therefor having a door, and guiding

means for the article moved into guiding position by movement of the door.

8. Mechanism for applying coating comprising an article support, means to rotate said support, a casing inclosing said article upon the support, a door for said casing, and 70 means adapted guidingly to engage a surface of the article to be coated, said means being connected to said door.

9. Mechanism for applying coating comprising in combination, an article support, 75 an inclosing casing for said article support, driving means for the article support a plurality of spraying devices adapted simultaneously to coat an end and the lateral surface of an article upon said article support 80 and means coöperating with said spraying devices for discharging therethrough a measured quantity of the coating material.

10. Mechanism for applying coating comprising an upright article support, an inclosing casing for the article support, a plurality of spraying nozzles within said casing, means to rotate said article support, said spraying nozzles being arranged simultaneously to coat the entire lateral surface and 90 the upper end of the article upon said article support and means coöperating with said spraying devices for discharging therethrough a measured quantity of the coating material.

11. Mechanism for applying coating comprising an article support, an inclosing casing therefor having means to contact with the lateral surface of the article upon said support, a door for said casing, and means 100 upon said door also to contact with the lateral surface of said article upon the support.

12. Mechanism for applying coating comprising a casing, an article support therein, means to drive the article support, a closed door for the casing, and means whereby the opening of the door stops the driving of the article upon the article support.

13. Mechanism for applying coating comprising a casing, an article support therein, 110 means to rotate said article support, a closed door for the casing, and means whereby the opening of the door stops the rotation of the article support.

14. Mechanism for applying coating comprising an article support 8, coating means 12, 13, 14, a casing 11 inclosing the article upon the support and said coating means, driving means 49, 50 for the article support, 120 a door 48 for the casing, and operative connections between said door and said driving means 49, 50.

15. Mechanism for applying coating comprising an article support 8, an inclosing casing 11 for the article upon the support, 125 driving means 49, 50 for the article support, a door 48 for the casing, a brake for the driving means 49, and means to apply said

brake and relatively to separate the driving means 49, 50 upon the opening of the door.

16. Mechanism for applying coating comprising an upright article support, a closing casing 11 for the article thereon, a door 48 for said casing, driving means 49, 50 for the article support, a brake 69 operatively con-

nected to said door 48, and means operatively connecting the bearing of the driving means 50 and the said door.

In testimony whereof I have signed my name to this specification. 10

HERBERT W. DAY.
